UNITED STATES PATENT OFFICE

PLINY N. JOSLIN, OF DE KALB, ILLINOIS

SKATE

Application filed October 3, 1928. Serial No. 309,995.

My invention relates to skates and more especially to a novel construction of roller skate which may without difficulty be interchangeably made into and used as an ice skate by the user, and among the other objects of the invention are to provide a construction which will permit a maximum range of adjustment between short and long lengths or sizes to fit the shoes of different skaters; to provide a skate of rigid and durable construction which may be economically produced in quantities; to provide a novel construction in which the heel plate and rear flange, as well as foot plate, are each made in one piece, and to reinforce the same in a novel manner to provide extraordinary rigidity and strength against the same sagging and looseness at the shank; to provide a shank girder of inverted channel or U-shaped cross section so as to present a much neater and more finished appearance by obviating the exposure of the edges of the shank; to provide novel truss supports and truck hangers for the front and rear or heel and toe plates and wheels thereof, which may be produced from novel blanks for connection with the foot plates and adapted to receive oscillating cushion trucks for the wheels or sled runners of novel construction, thus economizing in manufacturing costs; to provide means for rigidly clamping said parts in position when adjusted by sliding one on the other whereby they will positively remain in the desired adjusted position.

With the above and other objects in view, the invention consists in certain novel structure and arrangement of parts to be herein-after more particularly specified and pointed out in the claims.

In the accompanying drawings:

Fig. 1 is a side elevation of a roller skate constructed in accordance with the invention.

Fig. 2 is a plan view thereof.

Fig. 3 is a transverse sectional view across the shank girder taken on the section line 3-3 of Figure 2.

Fig. 4 is a sectional view taken on the section line 4-4 of Figure 5.

Fig. 5 is a longitudinal view taken on the section line 5-5 of Figure 2.

Fig. 6 is a side elevation of the skate made up as an ice skate with sled runners.

Fig. 7 is a sectional view of a modified construction of a shank girder taken on the section line 7-7 of Figure 8, and

Fig. 8 is a sectional view taken on the section line 8-8 of Figure 7.

Referring to the drawings in detail, and more especially to Figures 1 to 5 inclusive, 9 designates the heel plate of the skate which is stamped from sheet metal in a single blank and formed with an integral rear or heel flange 10 directed upwardly therefrom. At the juncture of the heel plate and flange, the blank is convexly rounded and slopes downwardly and rearwardly and then forwardly to a point beneath the heel plate at the sides where the metal is doubled on itself, as indicated at 11, the forward portions of the curved heel flange 10 preferably tapering and having their upper edges sloping downwardly in convex formation and curved rearwardly at the bottom or juncture of the sides of the rear flange with the side edges of the heel plate as shown.

The rear flange has inclined slots 12 at each side adapted to take a strap 13 which is equipped with a suitable adjustable buckle connection 14 for securing the skate around the ankle of the skater. The forward portion of the heel plate is tapered, the side edges beyond the doubled portions 11 being turned or curved downwardly as indicated at 15 to prevent exposure of the sharp edges as well as to stiffen the heel plate. These down-turned portions or curved flanges extend around into the front edge of the heel plate as indicated at 16 to provide shoulders 17 with a recess therebetween for accommodating and bracing the shank girder 18 which fits therebetween. This shank girder may be a solid flat bar of spring stiffness, or nearly so, but is preferably of inverted channel or U-shaped cross section, having side flanges 19 and a longitudinal slot 20 in the web portion thereof for receiving a clamping bolt 21 disposed through an opening in the front portion of the heel plate so as to clamp the heel plate in an adjusted position on the shank

girder by the tightening of the nut 22 on the bolt 21.

The toe or foot plate is designated at 23 and carries a clamping bolt 24 through an aperture therein near its rear end which engages an elongated slot 25 in the shank girder 18, spaced from the slot 20, and is similarly held by a nut 26 engaged on the bolt to clamp the toe plate in adjusted position on the shank girder according to the adjustment or degree of extension of the skate for extremely short or long sizes to fit the shoes of different skaters within a maximum range of adjustment.

In order to stiffen the toe plate, it is provided near the toe portion with a substantially V-shaped raised rib or bead 27, the outer edge of the toe plate at this point being left plain. The remaining portions of the sides of the toe plate are provided with downturned curved flanges 28 similar to the flanges 15 and 16 and terminating at the points 29 to provide shoulders facing inwardly toward each other in opposite directions for engaging the opposite sides or flanges 19 of the shank girder 18 in the same manner as the shoulders 17.

This construction serves to align the heel and toe plates while the flanges strengthen the same, as well as to keep the heel and toe plates from shifting or pivoting on the shank girder. At the forward portion of the toe plate, the latter is equipped with the usual toe clamp 30 slidably mounted therebeneath for adjustment toward and away from each other by means of an adjusting screw 31, as commonly employed. In addition, both the toe and heel plates are provided with opposed pairs of spaced slots 32, the slots in the toe plate being shown spaced apart a greater distance than the slots in the heel plate and preferably disposed in parallel relation and four in number on each plate and located nearer the inner ends of the heel and toe plates than their outer ends,—that is, the rear end of the heel plate and the forward end of the toe plate to which the toe clamps 30 are fastened.

The front and rear truck hangers are designated at 33 and 34, each being stamped from a single section of sheet metal to provide an intermediate transverse bight or mounting portion 35 with depending ends 36 apertured to provide parallel ears which form in part a housing for a rubber bumper 37 having a swinging bracket 38 pivoted thereto as by means of a pin 39. The bracket 38 consists of a section of metal rebent to provide the axle or spindle receiving portion 40 and upturned ends 41 which are apertured to form ears for receiving the pivot 39. These ends are also tapered as shown. A retainer plate 42 has slots 43 for receiving the ears 36 and fits upon the rubber bumper 37 and has downturned side portions 44 which prevent the bumper from unduly oscillating. The sides

of the hangers 33 and 34 are disposed in divergent relation in the blank and then bent at right angles to the intermediate portions 35 in opposite directions and parallel to each other. The sides of the hangers are referred to as being parallel, but the same results could be obtained by reducing the width of the shoulder at the top of the hanger and forming the brackets so that the sides at the top are wider apart than at the bottom. This would act as a brace, preventing the side thrust that under severe conditions might cause the bracket to buckle. When so bent upwardly, they are arranged with their top edges horizontal and formed with projections 45 to engage the slots 32 and are riveted or upset to secure the hangers to the heel and foot plates.

These hangers have their upper portions offset outwardly as indicated at 46 to provide upwardly facing shoulders 47 at the inner sides of the hangers which engage the bottom edges of the flanges 19 of the extension bar or shank member 18 which serves as a connection between the heel and foot plates by reason of the clamping members or bolts heretofore described. In the preferred construction, the front hanger 33 is made considerably longer than the rear hanger 34.

The axles or spindles 48 are received in the bearings or spindle-receiving portions 40 and take wheels 49 which may be of metal or cushion tread type. These spindles are generally in the form of bolts having a head 50 at one end and a nut 51 at the other end which adapt them to be readily detached in case it is desired to replace the rollers to interchangeably produce a roller or an ice skate. In making an ice skate, sled runners 52 are employed consisting of members of U-shaped cross section having openings 53 in the top portions 54 thereof conforming to the hangers and openings in the side portions which receive the axles. The bottom portions or runners are flanged outwardly, as at 55, which flanges are continued upwardly at the curved front portions, as shown in Figure 6 of the drawings.

In Figures 7 and 8, the extension bar or shank 18 is shown reinforced with a bar 56 which is similarly slotted to receive the clamping means 20 and 24. This bar 56 fits within the inverted channel-shaped member 18 between the side flanges 19 thereof so as to give additional strength to the shank portion. Otherwise, this construction is the same as heretofore described.

From the foregoing, it will be apparent that the construction of skate as described provides a maximum adjustment between short and long sizes and that the shank girder or extension bar fitting between the sides of the truck hangers and frictionally sliding between the shoulders thereof and the bot-

5 to 5 faces of the heel and toe or foot plates will provide a very neat construction of pleasing appearance which is very strong and rigid and which will not sag or become loose.

10 While I have shown and described my invention in a preferred form, I am aware that various changes and modifications may be made therein without departing from the 10 principles of the invention, the scope of which may be determined by reference to the appended claims.

I claim as my invention:

15 1. A skate comprising heel and toe plates, truck hangers depending therefrom and having side portions spaced apart and out-pressed upper portions forming upwardly facing shoulders, a girder extending at its ends into said hangers to frictionally engage the bottom faces of the plates and said shoulders, said girder comprising an inverted U-shaped member having downturned side flanges engaging the shoulders, and clamping means adjustably connecting the 25 plates and girder.

20 2. A skate having a foot plate, a truck hanger depending therefrom and having sides formed with out-pressed upper portions producing upwardly facing shoulders, a girder extending into said hanger and frictionally engaging the bottom face of the foot plate and said shoulders, said girder comprising a channel-shaped member with 25 downturned side flanges disposed against the inner faces of the out-pressed portions and with the edges thereof engaging the shoulders, and a connecting portion between said side portions adapted for connection with a spindle bracket.

25 3. A skate having a foot plate, a truck hanger depending therefrom and comprising a U-shaped member with a lower connecting portion and parallel sides having their upper portions pressed outwardly to provide upwardly facing shoulders at the inside, the upper edges of the side portions having lugs riveted through openings in the foot plate, a girder comprising an inverted channel-shaped member frictionally fitting between the shoulders and the foot plate and having a longitudinal slot therein and a clamping member carried by the foot plate and engaging the slot.

30 4. A skate comprising a heel plate having a rear flange provided with attaching means, a toe plate, said heel and toe plates having side flanges terminating in spaced relation at their inner ends forming recesses, an inverted U-shaped girder engaging the bottom faces of the heel and toe plates and fitting in said recesses, said girder having longitudinal slots, clamping means carried by the plates and engaging the slots, U-shaped truck hangers having top edges provided with lugs riveted to the heel and toe plates and having top edges provided with lugs riveted to the heel and toe plates

and having out-pressed portions forming upwardly facing shoulders adjacent said plates and in spaced parallel relation thereto, the side flanges of the girder engaging said shoulders, and traction means on the hangers.

70 5. A skate comprising a heel plate having a rear flange provided with attaching means, a toe plate, said heel and toe plates having side flanges terminating in spaced relation at their inner ends forming recesses, an inverted U-shaped girder engaging the bottom faces of the heel and toe plates and fitting in said recesses, said girder having longitudinal slots, clamping means carried by the plates and engaging the slots, U-shaped truck hangers having top edges provided with lugs riveted to the heel and toe plates and having out-pressed portions forming upwardly facing shoulders adjacent said plates and in spaced parallel relation thereto, the side flanges of the girder engaging said shoulders, said truck hangers having down-turned apertured ears at the front and rear of their connecting portions, a slotted plate fitting said ears against the bottom faces of said connecting portions and having downturned sides, a spindle plate having a spindle-receiving portion and upturned apertured ends aligned with the apertures of the ears, cushion members between said plates, and pivot members extending through the ears and cushions.

80 6. A skate comprising a heel plate having a rear flange provided with attaching means, a toe plate, said heel and toe plates having side flanges terminating in spaced relation at their inner ends forming recesses, an inverted U-shaped girder engaging the bottom faces of the heel and toe plates and fitting in said recesses, said girder having longitudinal slots, clamping means carried by the plates and engaging the slots, U-shaped truck hangers having top edges provided with lugs riveted to the heel and toe plates and having out-pressed portions forming upwardly facing shoulders adjacent said plates and in spaced parallel relation thereto, the side flanges of the girder engaging said shoulders, said truck hangers having down-turned apertured ears at the front and rear of their connecting portions, a slotted plate fitting said ears against the bottom faces of said connecting portions and having downturned sides, a spindle plate having a spindle-receiving portion and upturned apertured ends aligned with the apertures of the ears, cushion members between said plates, and pivot members extending through the ears and cushions.

85 7. A skate having foot and heel plates, truck hangers depending therefrom and each 90 95 100 105 110 115 120 125 130

10. A skate comprising a heel plate having a rear flange provided with attaching means, a toe plate, said heel and toe plates having side flanges terminating in spaced relation at their inner ends forming recesses, an inverted U-shaped girder engaging the bottom faces of the heel and toe plates and fitting in said recesses, said girder having longitudinal slots, clamping means carried by the plates and engaging the slots, U-shaped truck hangers having top edges provided with lugs riveted to the heel and toe plates and having top edges provided with lugs riveted to the heel and toe plates

7. A skate having foot and heel plates, truck hangers depending therefrom and each

comprising U-shaped members with parallel sides vertically arranged having outwardly offset upper edge portions forming upwardly facing shoulders at the inside, the bight 5 portions of the hangers being adapted to take brackets for supporting spindles, a shank girder extending between the plates and the shoulders of the hangers depending therefrom, and adjustable connecting means 10 between the plates and shank girder.

8. A skate having foot and heel plates, truck hangers depending therefrom and each comprising U-shaped members with parallel sides vertically arranged having outwardly 15 offset upper edge portions forming upwardly facing shoulders at the inside, the bight portions of the hangers being adapted to take brackets for supporting spindles, a shank girder extending between the plates 20 and the shoulders of the hangers depending therefrom, adjustable connecting means between the plates and shank girder, and a stiffening plate mounted in the channel of the shank girder and receiving said connecting means therethrough.

9. In a skate, a heel plate and a toe plate, said heel plate having an integral rear flange depending and doubled at its juncture with the heel plate, U-shaped truck hangers having top edges connected to said plates and having outwardly offset portions forming shoulders, an inverted channel-shaped shank girder fitting between the plates and shoulders with downturned flanges engaging the 30 shoulders, a supplementary shank girder fitting in the channel of the first-named shank girder between the side flanges thereof, said shank girders having registering longitudinal slots, and clamping means fixedly carried by the inner ends of the plates and engaging the slots of the shank girders to hold the plates in adjusted positions on the shank girders to vary the size of the skate.
